UNITED STATES PATENT OFFICE

146,261

DESIGN FOR A GARMENT HANGER

John L. Mack, Sr., Chicago, Ill.

Application March 20, 1946, Serial No. 127,699

Term of patent 7 years

(Cl. D80—8)

To all whom it may concern:

Be it known that I, John L. Mack, Sr., a citizen of the United States of America, residing at Chicago, in the county of Cook and State of Illinois, have invented a new, original, and ornamental Design for a Garment Hanger, of which the following is a specification, reference being had to the accompanying drawing, forming a part thereof.

Fig. 1 is a side elevational view of a garment hanger showing my new design; and Fig. 2 is a top plan view thereof.

I claim:

The ornamental design for a garment hanger, as shown.

JOHN L. MACK, SR.
